UNITED STATES PATENT OFFICE.

JOHN HUTZELMAN, OF WARNER SPRINGS, CALIFORNIA.

SHADE AND CURTAIN SUPPORTER.

1,278,934.

Specification of Letters Patent. Patented Sept. 17, 1918.

Application filed March 3, 1916. Serial No. 81,936.

To all whom it may concern:

Be it known that I, JOHN HUTZELMAN, a citizen of the United States, residing at Warner Springs, in the county of San Diego 5 and State of California, have invented certain new and useful Improvements in Shade and Curtain Supporters, of which the following is a specification.

The present invention has relation to certain new and useful improvements in shade and curtain supporting apparatus and as its primary object it contemplates the provision of an improved device of this character that is efficient in operation, strong and durable, 15 and which it is believed may be manufactured at a comparatively low cost.

Various other objects and advantages will become apparent during the continuance of the following description.

20 These and other objects which will become apparent are accomplished by such means as are shown in their preferred form in the accompanying drawings, described in the following specification and then more specifically pointed out in the appended claims.

In the drawings wherein like characters designate like parts throughout the several views:

Figure 1 is a fragmentary view of a window frame showing my invention, as in its 30 preferred embodiment, in connection therewith,

Fig. 2 is another fragmentary view showing the means for adjusting the curtain supporting poles,

Fig. 3 is a view in longitudinal section of means to cause the positive adjustment of the curtain supporting pole,

Fig. 4 is a view in detail illustrating an 40 improved bracket for supporting both the curtain and shade poles,

Fig. 5 is a view showing in detail a holding foot that is used in connection with the correlative curtain pole sections.

45 In Fig. 1 the curtain and shade roller are designated in their entirety by the numerals 10 and 11, respectively, and are supported by brackets 12 in an advantageous position with respect to the window frame A. The 50 curtain support consists of a pair of correlative sections 13 and 14, one of which is hollowed out a portion of its longitudinal extent as at 15 to receive a projecting end of the other. The section 14 is further provided with a longitudinal slot 16, that communicates with the bore or hollow of said

hollowed-out portion, and has a series of pockets 17 that merge into the slot. Consequently by providing the section 13 with a lug or projection 18 to seat in certain of 60 said notches, provision is made for retaining the respective sections in certain adjusted positions. Each of the sections are slightly enlarged at their outer ends as at 19, the enlargements being in turn provided with 65 holding feet 20, such as shown in Fig. 5. These feet are preferably formed of rubber or other nonslippping material and may be corrugated or serrated upon their engaging faces as at 21 in order to provide for a more 70 secure hold of the structure engaged.

Aside from the adjusting means above referred to, I also provide novel means to automatically adjust the respective hollow sections after they have been arranged in their 75 initial position with respect to the window frame. In accomplishing this purpose, the section 14 is divided into two halves (see Fig. 3), which have their inner ends oppositely screw-threaded, as at 22 for reception 80 into the oppositely screw-threaded bore 23 of a connecting sleeve 24. Consequently, it will be seen that by properly manipulating the connecting sleeve, the respective half sections may be drawn toward or forced 85 from each other in the manner that is readily apparent. In order to facilitate the proper manipulation of the connecting sleeve, I provide the same with a slidable collar 25 that carries on its inner face a 90 series of lugs 26 that may be engaged with the lugs 27 of the sleeve, as illustrated in Fig. 3. The collar is in turn provided with a handle portion 28 whereby its operation is greatly facilitated.

95 It is contemplated that the respective sections 13 and 14 be first arranged in connection with the window frame and adjusted by means of the pin or lug 18 so that the feet 20 engage the sides of the window frame, to 100 hold the same temporarily in place. After this has been accomplished, the connecting sleeve 24 may be actuated so as to cause the positive adjustment of the sections and force the engaging feet into binding engagement 105 with the sides of the window frame.

The respective sections 13 and 14 are further provided with suitable shade roller supporting brackets of the type shown in detail in Fig. 4. These brackets consist of 110 an upstanding arm 29 that is preferably formed integral with the respective sections

and bent at the point 30 so as to form a portion 31 to engage with the under-face of the horizontal cross-piece of the window frame, in the manner shown in Fig. 1. At its outer end the portion 31 is also bent as at 32 to 5 form another upstanding portion 33, a laterally extending portion 34 and a supporting portion 35. The supporting portion 35 of the brackets may be provided with a suitable cutout 36 for the reception of the ends of the shade roller, such as will be presently 10 pointed out.

By provision of the hinges 56, it will be noted that the members may be moved into or out of engagement with the periphery 15 of the roller, so as to securely retain the end of the shade or effect the release of the same, such as is obvious.

From the foregoing it is believed that the 20 advantages and main features of my invention will be readily understood and therefore further detailed description is deemed unnecessary.

In reducing my invention to practice, I 25 find that that form referred to herein as the most practical and preferred embodiment is the most efficient; but realizing that certain conditions will necessarily vary in concurrence with the adoption of my device, I desire to emphasize the fact that various minor 30 changes in the details of construction and in the arrangement and combination of parts may be resorted to when required without departing from the spirit and scope or sacrificing any of the advantages of my invention 35 as defined in the appended claims.

Having fully described my invention what

I claim as new and desire to secure by Letters Patent is:

1. A window shade and curtain pole support comprising telescoping members provided at their extremities with window jamb engaging elements, and adjacent their ends with integral shade supporting brackets, means for holding the members in an 40 adjusted position, one of said members being divided near its outer end and having the divided parts provided with right and left screw threads, respectively, a right and left threaded sleeve connecting the divided 45 parts, and a member mounted on said sleeve to effect a turning thereof to cause the said window jamb engaging elements to clamp the window jambs.

2. A window shade and curtain pole support comprising telescoping members provided at their extremities with window jamb engaging elements, and adjacent their ends with integral shade supporting brackets, each bracket comprising an upstanding portion, a forward portion engaging under the horizontal cross-piece of the window frame, a second upstanding portion, a lateral portion and a second forward portion, and means for positively lengthening the support to cause the jamb engaging elements 60 thereof to clamp the window frame jambs.

In testimony whereof I affix my signature in presence of two witnesses.

JOHN HUTZELMAN.

Witnesses:

A. K. TAYLOR,
MAUD ECLARK BATCHELDER.
